UNITED STATES PATENT OFFICE.

WALTER HAMMICK, OF PITTSBURG, KANSAS.

HEATING SYSTEM.

Application filed December 2, 1925. Serial No. 72,798.

This invention relates to heating systems, and is an improvement over the construction shown in my copending application for furnaces for kilns, filed November 21, 1924, Serial No. 751,365.

An object of the present invention is to provide a heating system in which suitable fuel, such as coal, coke, and the like, is burned, and the products of combustion then mixed with air in a secondary combustion chamber to obtain complete combustion.

A further object is to provide means for preheating the air employed in the secondary combustion chamber by radiation from the fire box.

A further object of the invention is the provision of means for supplying preheated air to the fire box.

By means of the invention, a temperature may be employed in the fire box below the fusing point of the clinker-forming, non-combustibles of the fuel, thereby eliminating the clinker trouble in the fire box and obtaining more uniform results with economy of fuel.

In the accompanying drawings, I have shown several embodiments of the invention. In this showing:

Figure 1 is a central vertical longitudinal view of a furnace kiln showing one form of the invention.

Figure 2 is a vertical transverse sectional view on line 2-2 of Figure 1.

Figure 3 is a similar view on line 3-3 of Figure 1.

Figure 4 is a central vertical longitudinal sectional view of another form of the invention.

Figure 5 is a horizontal sectional view on line 5-5 of Figure 4, showing the means for supplying the preheated primary air to the furnace.

Figure 6 is a vertical sectional view on line 6-6 of Figure 4.

Figure 7 is a similar view on line 7-7 of Figure 4, and;

Figure 8 is a detail view showing the manner of supporting the air conduits in the furnace.

Referring to Figures 1 to 3 of the drawings, A indicates a furnace which is formed with a fire box 1. The rear wall 2 of the fire box is spaced from the rear wall 3 of the furnace to provide a combustion chamber

The combustion chamber is divided by means of a checker wall 5. The rear fur-

nace wall is provided with an outlet 6 through which the heated air passes to the space 7 which leads to the kiln (not shown) or other device to receive the air. A chimney 8 is in communication with the chamber 4 and this chimney is covered by a door 9, so that the products of combustion may pass off through the chimney 8 when the door 9 is opened for starting up the furnace or when the kiln is not being used. Air is introduced into the top of the combustion chamber through a tubular conduit 10 which is horizontally arranged and which rests on the top of the fire wall 2 and passes through an opening in the front of the furnace. The passage of air into said tubular member may be controlled by a damper 11, arranged at the front end thereof. The air passing through this member is highly heated from the heat generated by the combustion of fuel in the fire box, this fuel being introduced through the usual fuel door 12 and air being admitted to the fire box through the usual door 13.

All of the parts are formed of fire resisting materials as they are subjected to intense heat and metals would soon be burnt out if used in the device. The mixture of the highly heated air passing through the conduit 10 with the products of combustion passing over the fire wall from the fire box into the combustion chamber will insure perfect combustion of said products, and this combustion is facilitated by the passage of the mixture through the checker wall 5 which is also highly heated. Thus, the air passing through the outlet 6 is heated to a high degree and is free of all impurities, such as soot and the like, so that it reaches the kiln in a perfectly clean state and thus will not soil the bricks or other material being treated in the kiln. The furnace may be run with a minimum amount of fuel and its operation is very simple, as there are no grate bars to burn out or become clogged with ashes. The space 14 at the top of the furnace is to be filled in with earth, as usual.

In the form of the invention shown in Figures 4 to 8 of the drawings, I have shown a furnace more adapted for use in heating systems and the like. As shown, the furnace is provided with a fire box 15 having an arch 16 arranged over it. The fire box is provided with a fire wall 17 at its rear end which is spaced at the top from the arch, as indicated at 18. The front of

- the fire box extends to the front wall 19 of the furnace which is provided with the usual fire door 20 and ash pit opening 21. A combustion chamber 22 is arranged rearwardly of the fire wall and extends to the rear wall 23 of the furnace. The rear wall may be provided with a suitable opening 24 for the final escape of the products of combustion.
- 10 As in the form of the invention heretofore described, I introduce preheated air into the secondary combustion chamber 22 together with the products of combustion from the fire box and this preheated air 15 causes complete combustion of the gases forming the products of combustion. The air is preheated by radiation from the fire box. As shown, a plurality of members 25 are supported on the under side of the arch 20 and these members are provided with openings 26 forming conduits which communicate with the combustion chamber 22 at their rear end. The front ends of these conduits extend through the front wall of 25 the furnace as indicated at 27. The side walls of the furnace are similarly provided with conduits for the passage of air to be preheated. As shown, the side wall is formed of bricks or the like, with the alternate bricks projecting, as indicated at 28. Between each pair of projecting bricks, I support a member 29 having a key 30 to enter the space between the projecting bricks and provided with a conduit 31. These conduits extend through the front wall of the furnace in the manner heretofore described in connection with the conduits 26 and at 35 their rear ends, they communicate with similar conduits 32 extending transversely of the furnace along the front of the fire wall 17. The inner ends of the conduits 32 communicate with upwardly extending conduits 33 having outlet openings 34, arranged at the top and rear of the fire wall, as shown 40 in Figure 4 of the drawings. Attention is called to the fact that the length of the connecting conduit 32, 33 for the lower longitudinally extending conduit 31 is greater than that of the others, and to compensate 45 for the increased resistance caused by the increased length, this connecting conduit is made larger in cross section, as shown in Figure 7 of the drawings and the cross section of each conduit decreases so that the outer and shorter connecting conduit is of the smallest cross section. This provides 50 equal resistance in each of the conduits and thus causes a substantially equal amount of air to pass through each of them.
- 55 In this form of the invention, I also provide means for delivering preheated primary air to the fire box. As shown, I provide a pair of conduits 35 on each side of the fire box extending from the front to the rear and communicating with a downwardly

extending passage 36. This downwardly extending passage communicates with the lower conduit 37 by means of which the air is carried forwardly and the forward end of this conduit communicates with a passage 70 38 extending transversely of the front wall to the ash pit opening.

The operation of the device will be apparent from the foregoing description. In the use of the heating system, a fire is generated in the fire box in the usual manner. Due to the secondary combustion, the temperature in the fire box may be maintained at a point below the fusing temperature of the non-combustible elements of the fuel, 80 thus eliminating all trouble due to clinkers. Air passing through the conduits 26 and 31 is heated by radiation. By providing the members 25 and 29 with curved outer faces, substantially parallel to the wall of the conduits 26 and 31, the amount of heat necessary to raise the temperature of the material forming the conduits is thus reduced and the preheating of the air facilitated. While the temperature of 800° to 900° may be 90 maintained in the fuel bed, the combustion of the fuel which starts in the fuel bed, continues throughout the fire box and the temperature around the conduits 26 and 31 is much higher, in the neighborhood of 2000° 95 F., which permits the secondary air to be preheated to a relatively high temperature before it is delivered to the secondary combustion chamber 22. In the secondary combustion chamber, the partially consumed 100 products of combustion from the fire box being mixed with the highly heated air from the conduits 26 and 31 are completely burned and all of the fuel value extracted therefrom, resulting in an economy of fuel 105 not possible where the combustion takes place solely in the fire box.

The passage of the primary air rearwardly through the conduits 35 and then forward through the conduit 37 permits the introduction of this air into the ash pit at a higher temperature and facilitates combustion in the fire box.

The walls of the furnace may be formed of the usual fire brick and the conduits 115 formed of suitable refractory material.

It is to be understood that the forms of my invention herewith shown and described are to be taken as preferred examples of the same, and that various changes in the 120 shape, size, and arrangement of parts may be resorted to without departing from the spirit of my invention or the scope of the subjoined claims.

I claim:

1. In a device of the character described, a fire box, an arch arranged over said fire box, a combustion chamber arranged adjacent said fire box and communicating therewith, and a conduit extending from the 130

exterior to said combustion chamber beneath said arch.

2. In a device of the character described, a fire box, a combustion chamber arranged adjacent said fire box and communicating therewith, a separating wall arranged between said fire box and said secondary combustion chamber, a plurality of conduits extending along the side walls of said fire box, and transverse conduits extending from the rear ends of said conduits along the forward side of said separating wall and communicating with said secondary combustion chamber.

15 3. In a device of the character described, a fire box, a secondary combustion chamber communicating with the fire box to receive the products of combustion therefrom, a conduit communicating with said secondary combustion chamber to deliver air thereto, said conduit passing through said fire box to preheat the air, and means for preheating the primary air delivered to said fire box.

4. In a device of the character described, 25 a fire box, an arch arranged over said fire box, a combustion chamber arranged adjacent said fire box and communicating therewith, a conduit extending from the exterior to said combustion chamber beneath said arch, a separating wall arranged between said fire box and said combustion chamber, and a plurality of conduits extending along the side walls of said fire box and then transversely along the face of 30 said separating wall, the ends of said conduits communicating with said combustion chamber.

5. In a device of the character described, 40 a fire box, an arch arranged over said fire box, a combustion chamber arranged adjacent said fire box and communicating therewith, a conduit extending from the exterior to said combustion chamber beneath

said arch to supply preheated air to said combustion chamber, and a conduit extending rearwardly of said fire box, thence forwardly and communicating with said fire box to supply preheated air thereto.

6. In a device of the character described, 45 a fire box, a combustion chamber arranged adjacent said fire box and communicating therewith, a separating wall arranged between said fire box and said combustion chamber, a plurality of conduits extending along the side walls of said fire box and communicating with the exterior, and transverse conduits extending from the rear end of said conduits along the forward side of said separating wall and communicating with said secondary combustion chamber, 50 said transverse conduits being of varying length and varying inversely in cross sectional area whereby substantially the same amount of resistance to the passage of air is afforded by each of said transverse conduits.

7. A furnace of the class described comprising a fire box, a combustion chamber in rear of the fire wall thereof and communicating with the box at its upper part, a 55 checker wall dividing the combustion chamber into two parts, a chimney connected with the combustion chamber, a door for the chimney, means for leading the heated air from the combustion chamber to the point of use, a tubular member passing through the front wall of the furnace and through the fire box and having its rear end resting upon the fire wall for introducing atmospheric air into the combustion chamber, said member being formed of fire resisting material and a damper at the front end of said member.

In testimony whereof, I affix my signature.

WALTER HAMMICK.
